CLAIM

The ornamental design for an orthopedic device, as shown and described.

DESCRIPTION

This application incorporates by reference U.S. patent application Ser. No. 15/672,593, filed on Aug. 9, 2017.

FIG. 1 is a perspective view of an orthopedic device;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof; and,

FIG. 7 is a bottom plan view thereof.

The broken lines in the various views depict portions of an orthopedic device and form no part of the claim.
